UNITED STATES PATENT OFFICE.

CHARLES LEMUEL SANFORD, OF WASHINGTON, PENNSYLVANIA, ASSIGNOR TO
SANFORD MANUFACTURING COMPANY, OF WASHINGTON, PENNSYLVANIA.

FLYING-MACHINE.

1,228,054.

Specification of Letters Patent. Patented May 29, 1917.

Application filed August 19, 1914. Serial No. 857,570.

To all whom it may concern:

Be it known that I, CHARLES LEMUEL SANFORD, a citizen of the United States of America, and resident of 218 South Wade avenue, in the city of Washington, county of Washington, State of Pennsylvania, in the United States of America, have invented certain new and useful Improvements in Flying Machines, of which the following is a specification.

The invention relates to improvements in flying machines as described in the present specification and shown in the accompanying drawings that form part of the same.

The invention consists essentially of the novel construction and arrangement of parts whereby the center of gravity and the weight carrying properties of the machine are comparatively low in relation to the supporting planes and the propelling and lifting mechanism permits of the poising of the ship and whereby the various details are so worked out as to increase the stability without decreasing the driving power.

The objects of the invention are to devise a flying machine of the hydro-aeroplane type that will be very useful for all purposes and particularly for maneuvers in the operations incidental to war, to increase the floating properties of the vessel in the air and thereby make it possible to land at a place otherwise not satisfactory, to enable such a vessel to carry increased weight and thus transport passengers, mails or war materials with great facility, to thoroughly protect all the parts of the machinery from exposure to the atmosphere and consequently from the effects of immediate contact with varying currents of air and generally to provide a flying machine of the hydro-aeroplane type of durable construction and serviceable for comparatively long distances and for landing and poising.

In the drawings Figure 1 is a perspective view of the machine.

Fig. 2 is a longitudinal mid-sectional view of the car showing the planes in cross section.

Fig. 3 is a rear end elevation.

Fig. 4 is a horizontal section on the line A—B in Fig. 3.

Fig. 5 is a cross sectional view of the car on the line C—D of Fig. 4.

Fig. 6 is a cross sectional view of the car on the line E—F of Fig. 4.

Fig. 7 is a perspective detail of a section of a plane.

Fig. 8 is a detail of the gear shifting mechanism.

Like numerals of reference indicate corresponding parts in each figure.

Referring to the drawings, 1 is the car here shown as having the vertical sides 2, the double bottoms 3 and 4, the gable roof 5 sloping from the central ridge to each side 2, the four sided pyramidal prow end 6 having a shaft bearing 7 at the apex of the pyramid, the top side of said pyramid prow extending up to the ridge of the roof 5 and straight across joining the blank walls 8 extending downwardly to the roof, the lower side of said pyramid extending downwardly in a direct line to the bottom 4 and intermediate of its length joined to the bottom 3, and the rear wall 9 extending to the gable roof 5 to the bottom 3 and joined to the bottom 4 by the inclined strip 10, this providing at the bottom of said car an enclosed space resembling the double bottom of a ship, the said space being of course air tight and thus providing increased buoyancy for the car.

11 is a shaft bearing centrally arranged in the rear wall 9 and in alignment with the shaft bearing 7.

12 are windows in the side walls of the car.

13 is a door in one of the side walls of the car.

14 are windows in the rear wall of the car.

The car 1 is preferably constructed of wood veneering covered with canvas and secured to a suitable frame though the material and the particular details in putting together and supporting said material are not essential to this invention, furthermore the exact shape of the car as described need not necessarily be adhered to in every instance during construction as circumstances may make it desirable to change the form.

15 is the motor and 16 is the motor shaft, the latter extending forwardly and rearwardly from said motor and carrying at the forward end one member 17 of a clutch coacting with a member 18 and at the rear one member 19 of a clutch coacting with a member 20. The clutch member 18 is mounted at the end of the shaft 21, the latter being journaled in the bearings 22 supported from

the flooring of the car. The clutch member 20 is mounted at the end of the shaft 23, the latter being journaled in the bearings 24 supported from the flooring of the car.

5 25 is the bow propeller shaft journaled in the bearings 7, 26 and 27 and carrying at the outer end beyond the prow the propeller 28 formed of a pair of blades.

29 is the rear propeller shaft journaled in 10 the bearings 30, 11 and 31 the bearings 30 being carried beyond the rear wall 9 by the brackets 32, said shaft 29 carrying at its rear extremity the propeller 33 formed of a pair of blades.

15 34 is a chain and sprocket drive from the shaft 23 to the sprocket wheel 34^a of the shaft 25 and on the coaction of the clutch members 19 and 20 imparting motion to the said shaft 25 and establishing the driving 20 connection from the motor 15 to the propeller 28 on the outer end of said shaft 25.

35 is a shaft journaled in bearings 36 and in two parts joined by the clutch members 37, said shaft at its forward end carrying 25 the gear wheel 38 meshing with the gear wheel 39, the latter being mounted on the shaft 23.

40 is a chain and sprocket mechanism connecting the shaft 35 with the rear propeller 30 shaft 29; thus when the clutch members 19 and 20 are in coaction, and the clutch members 37, the driving connection is established between the motor 15 and the propeller 33.

41 is a shaft journaled in the bearings 42 35 to one side of the bearings 26 carrying at its outer end within the pyramidal prow the bevel gear 43.

44 is a bevel gear slidably mounted on the bow propeller shaft 25 and operatively connected with the lever crank 44^a, said lever crank being pivotally suspended at 44^b to the bracket 44^c.

44^a and 44^c are rods operatively connected to the lever cranks 44^a at 44^b and 44^c respectively said rods being suitably connected to an operating lever at the operator's table.

By operating the rods 44^a the bevel gear 44 is brought into co-action with the bevel gear 43. When the rod 44^c is operated the 50 bevel gears 43 and 44 are separated thus stopping the motion of the propeller shaft 25.

45 is a chain and sprocket mechanism connecting the shaft 21 with the shaft 41.

55 46 is a shaft journaled in the bearings 47.

48 is a chain and sprocket mechanism connecting the shaft 21 with the shaft 46, thus when the clutch members 17 and 18 are in coaction the shaft 46 is driven by the 60 motor 15.

49 and 50 are horizontal beams preferably of channel formation, one of said beams projecting through the car 1 immediately to the rear of the pyramidal prow and the 65 other of said beams projecting through the

car adjacent to the rear wall, both of said beams in every instance projecting considerably beyond the side walls 2 and carrying at their ends the gear boxes 51.

52 are bearings in the beams 49 and 50 closed in by the caps 53 supporting the oil 70 cups 54.

55 and 56 are shafts journaled in the bearings in the beams 49 and 50 respectively and extending the complete length of said 75 beams carrying the bevel gear wheels 57 and 58 respectively intermediate of their length coacting with the bevel gear wheels 59 and 60 mounted at the ends of the shaft 46 thus establishing a driving connection between the 80 motor 15 and the shafts 55 and 56.

61 are vertical shafts journaled in the tops of the gear boxes 51 and in the bearings 62 supported in brackets from the top of the side walls and carrying at their lower ends the bevel gears 63 coacting with the bevel gears 64 at the end of the shafts 55 and 56 thus establishing an operating connection between the lifting blades 65 mounted on the top of the shaft 61 and the motor 15. 90

66 are shafts rigidly secured to the side of the car about amidship and intermediate of the height of the sides, said shafts having at their outer ends pivotally suspended therefrom the pontoons 67 which may be of any suitable shape though here shown as air tight scow shaped vessels, the bottoms of said pontoons being at a higher level than the bottom 4 of the car.

68 and 69 are vertical posts of metal or other suitable material projecting upwardly from the corners of the car 1 and considerably above the roof of said car and forming bow and rear plane posts respectively. 100

70 are rear plane posts extending upwardly from the car 1, one from each side thereof and in advance of the posts 69.

71 are bow plane posts extending upwardly from the sides of the car above the roof and behind the posts 68.

72 are fore and aft rails joining the post 69 to the post 70.

73 are fore and aft rails joining the posts 68 to the posts 71 and the posts 71 to the posts 70.

74 and 75 are parallel plane rods rigidly secured to the posts 69 and 70 respectively, the rod 75 being at a slightly higher elevation than the rod 74, said rods extending out at each side for an even distance and forming a support for the upper rear plane. 115

76 and 77 are plane rods secured to the posts 69 and 70 at the required distance below the rods 74 and 75 and arranged at the different levels the same as the rods 74 and 75 but not extending as far on each side of the machine as the said upper rods. 125

78 are the sections of the planes, each made the same and made of suitable light material having the ends 79 and a central 130

pivot 80 at each end from which extend above and below the rocking arms 81. These planes are secured in suitable pivot holes in the said plane rods and have the arms 81 connected to the various cords 82, the ends of which cords are brought within the car 1 for adjusting the positions of the sections of the planes in the navigation of the machine, said cords passing around various 10 pulleys 83 secured to the plane rods to facilitate the operation.

84 and 85 are the bow planes in detail constructed precisely the same as the rear planes and supported between the posts 68 and 71, both of said planes 84 and 85 being at a higher level than the corresponding rear planes.

86 are braces reinforcing the various plane rods.

20 87 are stays from the ends of the planes to the car.

88 is a rudder operated from within the car.

25 89 are the casters mounted in any suitable caster bearings and arranged in any way that will not interfere with the successful working of the machine.

90 is a pivoted plane secured between the posts 68 intermediate of their height connected by suitable cords or wires to the interior of the car so that said plane may be turned on its pivots in elevating and lowering the machine being the bow rudder for the vertical movements of the machine, that 35 is to say, up or down as the case may be.

91 is a switch board within the car 1, connections to which are made from the various devices operated in the use of the machine.

40 It may here be mentioned that the sections of the planes hereinbefore referred to have beveled side edges so that when they are closed the complete length of plane presents a perfectly flush surface and also that 45 the cords or wires connecting the sections to the interior of the car are preferably in each case duplicated to avoid accidents.

In the operation of the machine the car is lifted by the operation of the lifting blades which as will be seen operate independently of the tractive and propulsive propellers, said propellers remaining stationary during the first operation of rising from the ground or water. To effect the 55 elevation by means of the lifting blades the sections of the planes are turned on their pivots and held to a vertical position, also the altitude plane between the two fore posts thus the resistance is minimized there being only a skeleton frame and the sloping roofs of the car and the prow of said car. These lifting propellers continue to rotate and the sections of planes are closed after reaching the desired altitude and inclosing 65 these planes suitable stops are provided so

that they will fold in perfectly flat and present flush surfaces on the top and bottom, each plane being curved from the rear to the front end in an upward direction and as explained higher at the front 70 end so that the air flows into a temporary pocket and thus a more perfect floating plane is secured. The altitude plane is also turned from its vertical position and regulated for the proper vertical direction of 75 travel desired. The rudder at the rear end of the planes is of course utilized to determine the lateral directions of travel. Subsequent to the return and proper regulation of all these parts the tractive and propulsive propellers are set in motion by the co-action of the clutch members as explained then the rotation of the lifting blades is stopped and the machine continues on its 80 journey guided by the two rudders, one for upward and downward inclines and the other for making turns to the right or to the left.

In order to effect the proper lighting, say 90 in a small patch of ground or on shipboard the machine is brought to a state of poise and the propulsive propeller stopped while the lifting blades are again set in motion, the tractive propeller is then reversed by means of the bevel gears as already explained until such time as the flying machine remains stationary over the exact place of lighting then the machine will 95 gradually and quietly settle down by the operation of the sections of the planes. The 100 hydroplane features of this machine are very evident for the car is built in such a manner as to be a very good and safe vessel, not of course to stand any mighty sea but to float buoyantly and preserve the safety of the 105 machine during its travel or rest on the water. The pontoons are of course for the purpose of balancing the effect of the out-stretching planes and preventing the capsizing of the machine while stationary in the 110 water.

What I claim is:

1. In a flying machine, a car, a frame extending from said car, a plurality of planes supported by said frame, a plurality of lifting blades, vertical shafts supported by outriggers from said car and carrying said blades, a propulsive propeller, a tractive propeller, means for disconnecting the propulsive propeller and means extending to 115 said vertical shafts and said tractive propeller for coincidentally operating the latter in a reverse direction and the former in their normal direction.

2. In a flying machine, a car, a frame 125 built up from said car extending thereabove forming posts and front and rear rods for fore and aft sets of bi-planes, plane sections pivotally secured between said rods and completing the planes, means for op- 130

erating and connecting said plane sections to the car, a plurality of lateral beams extending outwardly from said car, vertical shafts secured and journaled at the extremities of said beams, lifting propellers mounted on said shafts, horizontal shafts on said beams operatively connected with said vertical shafts, a motor operatively connected with said horizontal shafts, a tractive propeller at the bow of said machine, a propeller shaft carrying said propeller and operatively connected to said motor independently of said lifting propellers, a propulsive propeller at the rear end of said machine, a shaft for said propulsive propeller operatively connected to said motor and driven co-incidently with said bow propeller and connections from said motor independent of the aforesaid connections for reversing the direction of rotation of said tractive propeller.

3. In a flying machine, a car, a motor contained in said car having its shaft extending from each end thereof, auxiliary shafts at the front and rear ends of said motor respectively, clutches between said motor shaft and said auxiliary shafts, a bow propeller shaft, a stern propeller shaft, a subsidiary shaft operatively connected to the rear auxiliary shaft and to the stern propeller shaft, a clutch mechanism intermediate of the length of said subsidiary shaft, a drive connection from said rear auxiliary shaft to said bow propeller shaft, a bevel gear mounted on said bow propeller shaft, a gear shaft suitably journaled and supported adjacent to said bow propeller shaft and shiftable, a bevel gear on said gear shaft coacting with the aforesaid bevel gear, a driving connection between said forward auxiliary shaft and said gear shaft, an intermediate shaft suitably journaled and extending longitudinally with the car, a bevel gear at each end of said intermediate shaft, a plurality of horizontal shafts at right angles to said intermediate shaft, coacting bevel gears mounted on said horizontal shafts and connecting them with said intermediate shafts, gears on the extreme ends of said horizontal shafts, vertical shafts at the extreme ends of said horizontal shafts, coacting gears on the lower ends of said vertical shafts, lifting propellers mounted on said vertical shafts, a tractive propeller mounted on said bow propeller shaft, a propulsive propeller mounted on said stern propeller shaft and planes supported above and by said car.

4. In a flying machine, a car formed of a hull having a tapering prow, a blunt stern, and a deck or roof sloping downwardly from a longitudinal central ridge and at the bottom thereof an air tight compartment and planes supported above and by said car.

5. In a flying machine, a car formed of a hull having a four sided pyramidal prow, a gable roof or deck, flat sides and stern and flat double bottoms forming an air compartment therebetween, shafts projecting laterally from said sides intermediate of the height thereof, pontoons pivotally swung from said shafts and planes supported above and by said car.

6. In a flying machine, a car formed of a hull having sides, prow, stern transom and deck or roof and central shaft bearings at the bow and stern, planes supported by and above said car, propeller shafts projecting through the bow and stern, a motor supported on the flooring of said hull below said shafts and operatively connected therewith and vertically and horizontally set rudders at the rear and front of said planes respectively.

7. In a flying machine, a car formed of a hull having a four sided pyramidal prow, a gable roof or deck behind said prow, a stern transom extending from said roof or deck and a double bottom forming an air chamber at the lower end, propeller shaft bearings arranged centrally in said bow and said stern transom, propeller shafts journaled in said bearings, a motor located on the flooring of said car in the interior thereof, auxiliary shafts connected with said motor shaft and operatively connected with said propeller shafts, a frame extending upwardly from said car and fore and aft bi-planes supported by said frame.

8. In a flying machine, a car formed of a hull having a tapered prow and a sloping deck or roof, stern transom, sides and bottom, posts extending upwardly in pairs from said car, bi-planes supported between said posts at the front and rear of said car, propeller shafts journaled in the prow and in the stern, a motor supported on the floor of said car in the interior thereof below said propeller shafts and operatively connected therewith propellers mounted on said shafts, a pair of channel beams, one projecting laterally from each side of the car immediately behind the prow and the other projecting laterally from each side of the car toward the rear end having bearings intermediate of their length and gear boxes at the ends, shafts journaled in the bearings in said beams, gears mounted at the ends of said shafts, a bevel gear on each of said shafts in the beams intermediate of the length thereof, a shaft extending fore and aft within said hull suitably journaled and operatively connected with said motor gears on the end of the latter shaft coacting with the bevel gears on said beam shafts, lifting propellers, vertical shafts carrying said lifting propellers, and journaled in said gear boxes, gears on the lower ends of said vertical shafts coacting with the gears on the

125
130

ends of said beam shafts and fore and aft bi-planes supported by and above said car and formed of pivoted sections operated from within the car.

- 5 9. In a flying machine, a car, means for driving said car, a frame extending upwardly from said car formed of posts in pairs and front and rear lower and upper plane rods, said front rods in each case 10 being slightly higher than the corresponding rear rods, plane sections having pins projecting centrally therefrom at the front and rear and pivoted in said front and rear rods and closing to form complete planes, 15 each of said sections having an upward curve from front to rear forming an air pocket on the underside of each plane and means for turning said planes on their pivots.

- 20 10. In a flying machine, a closed in car having a comparatively sharp prow and propeller shaft bearings front and rear,

propeller shafts in said bearings, propellers on said shafts, a motor beneath said shafts and operatively connected therewith, a plurality of lifting propellers, vertical shafts carrying said lifting propellers and operatively connected from without to the interior of said car, a frame supported above said car, bi-planes supported by said frame at the front and rear of said car and formed of a plurality of sections adapted to turn to a vertical position, an altitude rudder journaled horizontally in said frame above the prow of said car and a rudder journaled vertically at the rear of said frame; both of said rudders being operatively connected to mechanism within the car.

Signed at the city of Toronto, this 11th day of July 1914.

CHARLES LEMUEL SANFORD.
